(57) **CLAIM**

The ornamental design for a dental surgical kit, as shown and described.

DESCRIPTION

FIG. 1 is a perspective view showing our design for the dental surgical kit;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof.

FIG. 8 is a perspective view showing a first alternative embodiment of our design for the dental surgical kit;

FIG. 9 is a front view thereof;

FIG. 10 is a rear view thereof;

FIG. 11 is a left side view thereof;

FIG. 12 is a right side view thereof;

FIG. 13 is a top view thereof; and

FIG. 14 is a bottom view thereof.

FIG. 15 is a perspective view showing a second alternative embodiment of our design for the dental surgical kit;

FIG. 16 is a front view thereof;

(Continued)

FIG. 17 is a rear view thereof;
 FIG. 18 is a left side view thereof;
 FIG. 19 is a right side view thereof;
 FIG. 20 is a top view thereof; and,
 FIG. 21 is a bottom view thereof.

The broken lines are included for the purpose of illustrating portions of the dental surgical kit that form no part of the claimed design.

1 Claim, 21 Drawing Sheets
